UNITED STATES PATENT OFFICE.

WALTER L. FREUND AND FREDERIC B. MENNER, OF ST. LOUIS, MISSOURI.

BAKER'S MACHINERY.

Application filed October 8, 1925. Serial No. 61,289.

This invention relates generally to material-handling machinery. More particularly, our invention relates to a certain new and useful improvement in bakers' machinery of 5 dough-handling type and has for its chief object the provision of an efficient, labor and time saving, automatically operable charging-machine for the dough-mixer.

And with the above and other objects in 10 view, our invention resides in the novel features of form, construction, arrangements, and combination of parts hereinafter described and pointed out in the claims.

In the accompanying drawings,— 15 Figure 1 is a rear elevational view, partly broken away and in section, and Figure 2 is an end elevational view, of a dough-mixer charging machine embodying our invention.

Referring now more in detail and by reference characters to the drawings, which illustrate a preferred embodiment of our invention, A designates the stationary framework of the machine, which is of oblong rectangular form in plan and comprises a pair 25 of end-members spaced transversely of the machine and each including a pair of spaced parallel uprights or standards 1, 1, preferably of angle or other suitable structural shape, the frame end-members being rigidly bolted 30 to a floor or other support and the uprights of each pair being riveted or otherwise rigidly tied together by a plurality of connecting-plates 2 suitably spaced longitudinally of the uprights. Rigidly fixed, as by gusset- 35 plates 3, to, and disposed at the upper ends of, the pairs of uprights 1, are cross connecting-members 4, 4, also preferably of angle or other suitable structural shape, diagonally disposed brace-members 5, 5, being fixed, as 40 by gusset-plates 6, 6, to the uprights 1 and cross-members 4 at the upper corners of the framework.

B designates a traveling carriage or so-called elevator which is also of oblong rectangular form in plan and comprises oppositely disposed suitably spaced parallel channel-members 8, 8, disposed lengthwise horizontally between the frame end-members and rigidly tied together by cross-angles 9, 9. 50 Depending vertically from and at the corners of the connected members 8, 9, are angles 10, which latter at their lower ends and at the opposite ends of the carriage are tied together by cross-angles 11.

55 Fixed upon the plates 2 and extending ver-

tically or longitudinally of the frame-work intermediate the uprights 1 of each frame end-member, are oppositely disposed channels 12, 12, having their flanges presented inwardly of the frame-work and providing 60 ways or tracks for suitable rollers 13, 13, suitably mounted for rotation in brackets 14 fixed to the angle-members 9 and 11 of the carriage B.

Suitably fixed upon and substantially 65 forming part of the frame-work A, is a cross-beam 15, supporting a suitable preferably electrically actuatable hoisting-mechanism C of any standard or approved construction, which mechanism includes cables 16 reeved 70 about suitable pulleys mounted for rotation in a block 17 suitably fixed, as at 18, to the carriage or elevator B, the actuation of the hoisting mechanism C being preferably controlled at an end of the frame-work A, as 75 shown, by depending pull-cords 19, 19, attached at their upper ends to a rock arm or member 20 fixed upon the rotatory control-shaft 21 of the hoisting-mechanism. We might here state that for automatically controlling the actuations of the hoisting-mechanism C and consequently also the ascending and descending travel of carriage B upon the frame-work A, there preferably depends 80 from the outer end of an arm 22 fixed at its other end on the shaft 21 a rod 23 held loosely in position relatively to the adjacent frame end-member by a suitably slotted bracket 22a. Fixed on rod 23, is a suitably spaced 85 pair of blocks 24, and carried by the elevator B to slidably travel on the rod 23 intermediate the fixed blocks 24, is a suitably slotted bracket 25 adapted on the upward travel of carriage B to engage the upper block 24 to trip the shaft 21 to stop actuation of the hoisting mechanism and thereby limit upward travel of the carriage B and adapted on the downward travel of the carriage to engage the lower block 24 to likewise trip the shaft 21 to stop actuation of the hoisting 90 mechanism and thereby similarly limit downward travel of the carriage.

D designates a so-called trough-dumping member, which includes end-members 26 preferably of plate formation provided at 105 their upper and lower margins with flanges 27, 28, respectively, presented inwardly. Riveted or otherwise fixed to said upper flanges 27 and rigidly connecting said end-plates 26 at the front or entrance-side of mem- 110

bers D, is a cross-angle 29. Also fixed to, and rigidly at the rear upper corners of the member D connecting, said end-plates 26, is a channel-member 30 having its flanges presented rearwardly, as best seen in Figure 1, and riveted or otherwise fixed to and upon the channel 30, is a skirt shaped plate 31 flanged at its opposite side margins, as at 32, and providing a discharge-chute, which is normally, as when the carriage B is in fully lowered position, presented upwardly relatively to the frame-work A, as shown in full lines in the drawings.

Riveted or otherwise fixed to said end-plate lower flanges 28 and rigidly at the lower rear corners of member D connecting said end-plates 26, is an angle 33, and re-inforcing the member D, is a strut 34 and diagonal braces 35, suitably fixed to said rear upper channel 30 and rear lower angle 33, as best seen in Figure 1.

The member D is thus open both at its front and lower sides to readily receive a dough-containing trough E, illustrated in dot-and-dash lines in the drawings, which trough, when the member D is in lowered or normal position, is conveniently rolled into the member D at its open front side to rest upon the bottom or lower flanges 28 thereof, which flanges, during movement of the elevator B longitudinally of the frame-work A, provide supporting or carrying members for the inserted trough E.

Fixed crosswise upon the depending angles 10 and at each end of the carriage B, are spaced pairs of angles 36, which provide or form cross-trackways for rollers 37 mounted for rotation on stub-shafts 38 suitably fixed, as at 39, rigidly upon and laterally projecting outwardly from the end-plates 26 of the member D. By means thus of the stub-shafts 38 and their roller-bearing connection with the trackways 36, the member D not only is movable with the elevator B longitudinally of the frame A, but also is pivotally swingable or tiltable relatively to the elevator B and frame A during movement of the elevator B longitudinally of the frame. At the same time, it will be noted, the rollers 37 are adapted to travel in the trackways 36 crosswise of the frame end-members to freely effect a shifting of the supporting-pivots 38 of the member D upon the elevator B and thereby maintain a constant radius during swingable actuation of member D about its swingable or tiltable center, shortly to be described, as the member D is moved longitudinally of the frame A with the elevator B.

Riveted or otherwise fixed to and at the lower end of the frame-uprights 1 at the front of the machine, are relatively short angles 40 extending for part of their length longitudinally of and with the uprights 1 and then arcuately bent, as at 41, to project obliquely outwardly and upwardly, as at 42,

relatively to the frame-work A, the angles 40 providing trackways for rollers 43 carried for rotation upon angle-brackets 44 fixed to and upon the lower angles 28 of end-plates 26 of the member D.

Riveted or otherwise rigidly fixed upon the rear uprights 1 of the opposite end-members of the frame A and disposed suitably intermediate the length of the frame end-members, are rearwardly presented plates 45 rigidly supporting adjacent their upper ends oppositely disposed inwardly presented studs or stub-shafts 46, adapted for pivotal engagement with which studs or shafts 46 in the operation of the machine, for purposes shortly appearing, are U-shaped members 47 forming part of brackets 48 riveted or otherwise fixed to upwardly presented flanged end-extensions 49 of the member D, said extensions 49 being riveted or otherwise rigidly fixed to the end-plates 26 and channel 30 of member D and said U-shaped brackets 48 being normally presented upwardly, as shown. Fixed upon the inner faces of the plates 45, are suitably spaced angles 50 which provide retaining guide-ways for the brackets 48 in the actuations of the dumping-member D, now to be described.

In use and operation and assuming first that the elevator B and its carried trough dumping-member D are in normal or fully lowered position, as illustrated in full lines in Figure 1, a trough E is rolled into the member D to rest upon its lower flanges 28. The left-hand cord 19, reference being had to Figure 2, is now pulled to effect elevating actuation of the hoisting mechanism C, whereupon the elevator B is caused to ascend or travel upwardly within and upon the frame-work A, throughout the travel of the elevator B its rollers 13 smoothly working in the trackways 12. As the elevator B is so caused to travel upwardly in the frame A, the dumping-member D and its carried trough E first travel upwardly in a straight path in and relatively to the frame A until the rollers 43 approximately reach the arcuated bend 41 in the trackways 40, at which time the parts are so relatively proportioned that the U-shaped brackets 48 have reached and pivotally engage with the fixed studs 46. On now continued upward travel of the carriage B, the dumping-member D, being engaged, as described, at its brackets 48 with the fixed studs 46, will be pivotally swung or tilted, with the fixed studs 46 as a center, through an arc of approximately 130°, so that, when the elevator B has reached the limit of its upward travel as determined by engagement of the bracket 25 with the upper block 24, the dumping-member D will occupy the fully swung or tilted position thereof illustrated in dot-and-dash lines in Figure 2, in which position of the dumping member D, its contained trough E will be similarly

tilted, so that the contents thereof may freely discharge through the chute 31 into the adjacent dough-mixer F.

The contents of the carried trough E having been discharged into the mixer F, the other or right-hand cord 19, reference being again had to Figure 2, is actuated to effect descending actuation of the hoisting mechanism C, whereupon the carriage B and its carried parts are caused to travel downwardly within and relatively to the frame A, during which descending movement the dumping-member D is, in like manner, reversely tilted to assume, when the elevator B has reached the limit of its downward travel, as determined by engagement of the bracket 25 with the lower block 24, full initial or normal position.

We might here state that, in the upward travel of the member D with the carriage B, the initial swingable movement of the dumping member D is freely permitted by the obliquely outwardly and upwardly disposed portions 42 of the tracks 40, upon which track-portions the rollers 43 ride outwardly in the upward travel of carriage B, and which track-portions similarly guide the rollers 43 to and upon the straight tracks 40 in the return of the dumping member D to normal position on downward travel of the carriage B, that the flanges 50 of the plates 45, through engagement with the brackets 48, retain the dumping-member D in operative position relatively to the carriage B and the frame-work A throughout such pivotal or swinging movement thereof, that the rollers 37 freely permit, as stated, a shifting of the supporting pivots of the dumping-members D throughout such swingable movement thereof, and that the upper cross-member 29 of member D securely retains the trough E within the member D when the same is in full tilted or discharge position.

We are aware that changes in the form, construction, arrangement, and combination of the several parts of our new machine may be made and substituted for those herein shown and described without departing from the nature and principle of our invention.

Having thus described our invention, what we claim and desire to secure by Letters Patent is:

1. In a machine of the class described, in combination, a stationary frame-work, a car-

riage adapted for travel longitudinally of the frame-work, means for actuating the carriage longitudinally of the frame-work, trackways fixed on the carriage and disposed transversely to the frame-work, a trough-carrying and dumping member disposed within the carriage, rollers mounted upon the ends of said member and fitting in said trackways for supporting said member for movement both with the carriage longitudinally of the frame-work and swingably relatively to the carriage and frame-work, said rollers being adapted for movement on said trackways for shifting the point of connection between the carriage and said member during movement of the carriage and said member longitudinally of the frame-work, and means including inter-engageable members upon the frame-work and said member for effecting pivotal actuation of said member relatively to the carriage and frame-work during travel of the carriage longitudinally of the framework.

2. In a machine of the class described, in combination, a stationary frame-work, an elevator movable longitudinally of the frame-work, oppositely disposed studs fixed on the frame-work, trackways on the elevator transversely disposed to the frame-work, a dumping-member, rollers upon the dumping-member fitting for rolling movement in said trackways during movement of the elevator longitudinally of the frame-work, said rollers in their engagement with said trackways supporting the dumping-member for swingable movement relatively to the elevator, means for actuating the elevator and its carried dumping-member longitudinally of the frame-work, second trackways fixed upon, and disposed partly in parallel and partly in obliquely outwardly and upwardly relation to, the frame-work, brackets fixed upon the dumping-member adapted for engagement with said studs during movement of the elevator longitudinally of the frame-work, and rollers carried by the dumping-member for movement upon said second trackways in the longitudinal and swingable movements of the dumping member relatively to the frame-work.

In testimony whereof, we have signed our names to this specification.

FREDERIC B. MENNER.
WALTER L. FREUND.
